Primary Examiner—Susan Moon Lee(74) *Attorney, Agent, or Firm*—Mark D. Miller; Marcus N. DiBuduo**(57) CLAIM**

I claim the ornamental design for a beehive, as shown and described.

DESCRIPTION

FIG. 1 is a front perspective view of the beehive showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.
